JOSEPH A. GROEBLI, OF NEW YORK, N. Y.

SHUTTLE MECHANISM FOR EMBROIDERING-MACHINES.

1,126,987.

Specification of Letters Patent.

Patented Feb. 2, 1915.

Application filed December 18, 1911. Serial No. 666,467.

To all whom it may concern:

Be it known that I, JOSEPH A. GROEBLI, a citizen of the United States, and a resident of the city, county, and State of New York, have invented certain new and useful Shuttle Mechanism for Embroidering-Machines, of which the following is a specification.

My invention relates to a shuttle mechanism for embroidering machines of the large type which employ a movable tambour frame upon which the fabric is carried. In embroidering machines of this type the fabric is stretched upon a large tambour frame which is moved in various directions and extends to cause the stitching mechanism to produce the desired design upon the fabric. Besides a large number of needles arranged in a plurality of rows along the machine there are usually provided as many borers and as many stupfels as needles, which, for reasons of construction are generally arranged above or below, or above and below the needles, and they operate to bore the required perforations in the fabric as the design may require, and to smooth the edge of the apertures after the same have been provided with stitches around their edges. When the fabric is to be perforated, the needles are thrown out of operation, and if the boring is to take place near the points where the last stitches were made by the needles the fabric must be moved a distance substantially equal to the distance between the row of needles and the row of borers, on the one hand, or the row of stupfels on the other, and this movement is usually greater in extent than the movement generally required during any given stitching operation.

As before stated, the needles are stopped before the boring operation commences with the needles out of the fabric; and at the same time the shuttles are brought to a stop with their thread delivering apertures approximately in line with the respective needle and thread apertures in the throat plate; and the stopping of the needle and shuttle mechanism is usually caused by stopping the main shaft of the embroidering machine. When the shuttles come to a stop just preceding a boring operation there may be slack loops in the shuttle threads between the shuttles and throat plate caused by the descent of the shuttles from the highest position to the position described above. This loop or slack may be sufficient to permit the

frame to move freely as far as may be required, but often it is not. Therefore, when the fabric is moved to position it for the boring operation as above described, it often happens that the fabric has to pull out threads from the several shuttles as it is moved, and as the fabric movement is sometimes comparatively long during this operation, considerable stress is placed upon the fabric by the shuttle threads, which is not only apt to injure the quality of the embroidery, but the movement of the fabric is also liable to strain the shuttle threads to the point of breaking them. This is so, partly because the pull on the threads is not in a direct line from the shuttles but against the throat plate. Sometimes the fabric has to be moved over considerable distances from one part of a design to another where no intermediate stitches are desired or permitted. In this case the fabric makes a number of successive movements while the stitching mechanism is inoperative.

The object of my present invention, among other things, is to relieve the strain upon the fabric by imparting preferably to the shuttles themselves a supplemental or secondary movement preferably every stitch period during the boring or stupfel operation or while only the fabric frame moves and the stitching operation is disconnected, in order to pay out enough thread from each shuttle to allow the fabric to move freely so the usual stress of drawing thread out of the shuttles will no longer come on the fabric. During this shuttle movement the shuttles draw on their threads against the throat plate rather than directly against the fabric, so that the stress is not materially borne by the fabric.

To accomplish the above objects I impart a movement to the shuttles preferably at every stitch period while the fabric frame alone operates or while the fabric frame and the boring or stupfel mechanisms operate and I prefer to impart this movement after the embroidering machine shaft is disconnected for throwing out the needle and shuttle mechanisms. I prefer to combine my present device in such a manner with the ordinary shuttle mechanism, that but few extra parts will be required, thereby making the present device very simple in its application.

My invention is not necessarily confined

to the accomplishment of the above as it may be used in other instances where a secondary movement is to be imparted to the shuttles while the usual shuttle movement takes place.

My invention in its operation and usefulness will be more clearly understood from the detailed description hereinafter.

In the drawings forming a part of this application, Figure 1, is an elevation of part of the shuttle mechanism of an embroidering machine, showing the embodiment of my invention in its simplest form, Fig. 2, is a cross section thereof, taken on the line 2—2 of Fig. 1, Fig. 3, is an elevation of the shuttle and throat plate and Fig. 4 is a detail view of the jacquard connection for shifting the bowl to affect one of the shuttle drives.

In Fig. 3, I have shown the fabric 1, which is moved periodically with the tambour frame in the usual manner. Parallel with the fabric is the throat plate 2, having an aperture 3, in line with the path of the needle 8^a, and this is duplicated as to each needle in the customary manner. The throat plate is on the face of the shuttle track 5, and the shuttle 6, reciprocates in its track in order to pass through the loops formed behind the fabric by the thread of the sewing needle. This is the ordinary arrangement of the sewing devices. If the last stitch preceding the boring action were made at the point 7, in the fabric, while the point was opposite the needle, and the aperture 3, in the throat plate, and it is desired to bring the fabric down so that the point 7, will come nearly in line with the bore point 8, ready for the boring operation, there will be no substantial pull on the shuttle thread so long as there is a loop 9, in the shuttle thread between the shuttle and throat plate 2, because the fabric only has to draw on this loose loop. But after this free thread outside the shuttle has been used up by the movement of the fabric frame, then the fabric must draw the thread out from the shuttle against the action of the shuttle tension: and as the pull of the fabric on the thread is at an acute angle to the intermediate throat plate, the latter increases the resistance on the thread. As there are usually hundreds of shuttles in such a machine, the stress on the fabric under such conditions may become considerable and my object is to relieve this stress.

When the ordinary shuttle mechanism is disconnected by the stopping of the embroidering machine shaft leaving all the shuttles in the position shown in Fig. 3, I impart a movement to the shuttles, preferably downwardly from the position shown in Fig. 3, sufficient to draw out enough thread for the fabric movement above set forth, and then upwardly to the position shown in Fig. 3. This will leave a loop 9,

in the shuttle thread sufficient for the movement referred to. The shuttle threads may have more or less of a loop before this movement takes place, in which case there will either be no additional thread drawn off, or only enough to increase the existing loop to the desired extent. As this movement of the shuttle is parallel with the throat plate 2, the shuttle pulls on its thread against the throat plate at an angle to the aperture 3, and therefore the pull on the thread exerts very little, if any, stress upon the fabric.

As the shuttle mechanism is usually operated by the main shaft of the embroidering machine and such shaft is stopped when the usual shuttle and needle movements are to stop I operate my improved device from a source of power which is in operation when the main embroidering machine shaft is idle and for this purpose I prefer to operate the device from the shaft of the jacquard which operates the embroidering machine. As the jacquard and embroidering machine are both well known structures, I have shown only so much thereof as is necessary to teach the application of my invention. A complete jacquard may be seen by reference to my U. S. Patent No. 528632. Reference will also be made herein to my U. S. Patent 593208, dated Nov. 9, 1897.

In the drawings the shaft 10, is the main shaft of a jacquard and corresponds with the shaft of my said Patent 528632 of November 6, 1894. This is in the present showing arranged at right angles to the main embroidering machine shaft 11. The jacquard shaft operates at all times that the embroidering machine is in operation, while the shaft 11, is usually stopped whenever the needle and shuttle mechanisms are to go out of operation. This latter occurs, temporarily, when special function devices such as borers, stupfels, and like devices are to be operated and as this is well understood in the art the details of such actions will not be set forth herein. A disconnecting mechanism is shown in my U. S. Patent No. 911235 dated February 2, 1909.

In Fig. 1, I have shown a plurality of shuttle tracks 12, of usual construction, which are disposed in an upright, oblique, position in close proximity to each other and shuttles 6, are arranged to reciprocate in their individual tracks. The shuttles are reciprocated in their tracks by means of a shuttle drive bar 13, which has the usual shuttle engaging pins 14, all of which are well understood in the art. To a supporting bar 15, is secured a journal socket 16, in which reciprocates the rod 17; the latter is connected with a member 17^a, on the drive bar 13, so that reciprocations may be imparted to the drive through the rod 17.

On a suitably supported shaft 18, is fulcrumed a bell crank lever having one arm

19, provided with a pin 20, which engages in the fork 21, on the lower end of rod 17, for the purpose of reciprocating the latter. The operating force is applied to the other arm 22, of this angle lever. I have shown an operating bar 23, which is preferably operated from the main shaft 11. On the latter is arranged, loosely, a guiding block 24, and the bar 23, has a rectangular opening 25, the upper and lower edges 26, 27, of which travel in contact with the block 24, the opening being longer than the block to permit the bar 23, to be reciprocated relatively to the main shaft. The bar 23, is provided with rollers 28, 29, arranged on suitable studs 30, and between these rollers engages a cam 31, which is mounted on the main shaft, to move therewith. As the main shaft revolves, the cam 31, acting on the rollers 28, 29, will cause reciprocations in the bar 23, in the direction of its length, and the block 24, supports this end of the bar and also guides it. The bar 23, operates the lever 19, 22, through a connection which permits the special motion herein referred to, to be imparted to the shuttle drive through the bar 17. On the end of bar 23, I have provided a stud 32, on which fulcrums an arm 33, and this latter is fulcrumed at 34, to the arm 22, of the bell crank lever. I have arranged in an ear 35, on the bar 23, a reciprocating rod 36, the purpose of which is to engage in a slot 37, in the end of the arm 33, for the purpose of locking the latter. When the arm 33, is locked by the bar 36, the former is fixed relative to the bar 23, as shown in the drawing; in which case the arm can not rock on its fulcrum 32: and in this condition the shuttle mechanism is only operated by the movement imparted through the bar 23, from the main shaft 11, which is the movement imparted for the ordinary shuttle operation.

On the jacquard shaft 10, I provide a cam 38, in the groove 39, of which engages the bowl 40, on a lever arm 41. This arm is secured upon a second shaft 42. The shaft 42, corresponds with the shaft on which the hub K. is mounted and the arm 41, with the arm k of my said Patent No. 593208, and preferably operates the same devices, that is, the arm k of my said patent disconnects the embroidery machine shaft from the jacquard shaft and the mechanism therefor shown in my said Patents 593208, and 911235 is preferably employed in connection with the present device.

In Fig. 1, I have shown the pin 66, of the bowl 40, arranged to slide in the hub 67, on the end of lever arm 41, at right angles to the face of cam 38. There is shown an arm 68, engaging in a slot 70, of the pin 66, for the purpose of reciprocating the bowl, and the arm 68, is to be operated in well known manner by a jacquard dropper, the same as the arm k²² of my said Patent No. 593208.

On the shaft 42, I have provided an arm 43, to which is fulcrumed a depending rod 44. To the latter is secured the sleeve 45, of a fork 46, the bifurcated end 47, of which straddles a pin 48, on one arm 49, of an angle lever. The latter is fulcrumed to the bar 23, at the point 50, and one arm 51, thereof is fulcrumed to the locking bar 36. The lower end of the rod 44, is connected with an operating rod 52, which it is adapted to raise and lower. The rod 52, has on one end, a cam recess 53, and on the underside it has a recess 54, for engagement with a locking pin 55, which is suitably and stationarily supported. Inclines 56, are provided on each side of the recess 54. On the jacquard shaft 10, I provide a cam 57, having a flange 58, most of which is straight, but one portion 59, of which curves laterally. This cam is adapted to operate the rod 52, by engagement with the cam slot 53, as will be apparent hereinafter. One end of the rod 52, is fulcrumed to an arm 60, of a bell crank or angle lever, which rocks from a stationary stud 61, suitably supported. To the other arm 62, of this lever is fulcrumed a link 63, and the latter is also fulcrumed preferably to the stud 32, for the purpose of rocking the bar 23.

Operation: During the regular shuttle operations the parts are in the condition shown in Fig. 1. That is, the bar 52, is out of engagement with the cam 57, and is held stationary by the pin 55, which engages in the recess 54: and the locking bar 36, engages in the recess 37, of the arm 33. The movement of the main embroidery machine shaft is imparted to the shuttle drive as follows:—The cam 31, acting on the rollers 28, 29, reciprocates the bar 23, and this bar being connected with the lever 19, 22, causes the latter to rock on its fulcrum 18. The other arm 19, of this lever reciprocates the rod 17, and this latter being connected with the shuttle drive causes the shuttles to be reciprocated in their tracks. This condition continues during the regular operations of the needle and the shuttle mechanisms but when the stitching operations are to be suspended pending the operation of special devices, such as the borers, a change in the present mechanism occurs.

When the embroidery machine shaft is to be stopped through the mechanism shown in my said Patent No. 911235 the bowl 40, is thrown into the groove of cam 38, and the action of the cam causes the lever arm 41, to rock, and with it the shaft 42. As the arm 43, is secured to this shaft it will be moved upwardly by the rocking of shaft 42, and in so doing it causes two actions in the subsequent elements. When the arm 43, and its rod 44, move upwardly the fork 46, also goes upwardly causing the lever 49, 51, to be rocked in opposition 180

to its spring 64. This will draw the rod 36, out of locking engagement with the arm 33, leaving the latter free to move relative to the bar 23. The rising of arm 43, and rod 44, raises the bar 52, until its cam pocket 53, straddles the flange 58, of cam 57, on the jacquard shaft. It is to be understood that the rocking of arm 41, causes through the mechanism shown in my said Patent No. 10 911235, the disconnection of shaft 11, from shaft 10, leaving the former idle and the bar 23, ceases to reciprocate. When the cam pocket 53, is thrown into engagement with the cam 57, the latter is in operation because 15 the jacquard shaft continues to operate. The action of cam 57, on the pocket 53, will cause the rod 52, to reciprocate, which in turn will rock the lever 60, 62, and move the connecting link 63, up and then down. The 20 movement of link 63, rocks the left end of bar 23, which latter, in this operation fulcrums from the supporting block 24, turning on the main embroidering shaft 11. As the arm 33, is now unlocked it is free to 25 fulcrum from the stud 32. If, for instance, in the upward movement of the link 63, the point 32, is moved to the dotted position 65, then the arm 33, acting on the lever arm 22, will cause the latter to rock on its fulcrum 30 18, and assume substantially the position indicated in dotted lines. That is, the movement of link 63, upwardly rocks the lever arm 22, to the left, and the arm 19, will consequently move downwardly and the 35 same movement is imparted to the shuttles. When the shuttles move down, in case they have no free thread they will draw on their respective threads against the friction of the throat plate, and this will cause thread 40 in the shuttles to draw out, until the downward movement of the shuttles ceases. The shuttles may have more or less free thread, but when the shuttles move down they will draw out enough thread, if there is not already enough out, to accomplish the purpose 45 herein set forth.

When the cam 57, has turned a partial revolution the bar 52, lever 60, 62, link 63, and bar 23, will be returned again, and 50 through the arm 33, lever 22, 19 and rod 17, the shuttles will be raised to their former position with their apertures 6^a, approximately in line with the aperture 3, in the throat plate. There will then be a loop 55 9, of free thread from each shuttle sufficient to permit the fabric to be moved for the boring or other operation and in moving the fabric draws off enough of the loops 9, for this purpose without straining the fabric. The cam 57, continues to reciprocate the rod 52, preferably at every stitch period so long as the embroidering machine shaft 60 is disconnected; that is, so long as the arm 43, remains up. Therefore, the shuttles are 65 periodically lowered, so that if loops 9, have

been taken up, more is drawn off the shuttles to allow for any additional movement of the fabric. When the bowl 40, is again pushed into the groove of cam 38, by the device shown in my said Patent 593208 for 70 moving the bowl b^3 , of my said patent, the arm 43, herein will be swung back to its first position. This will lower the arm 43, and rod 44, causing the lowering of the end of rod 52, until the cam pocket 53, disengages from the cam 57, and reengages with the holding pin 55, when the rod 52, will no longer reciprocate. The downward movement of the rod 44, acting through the fork 46, rocked the lever 49, 51, back to its former position, and caused the rod 36, to reengage and lock the arm 33. The latter will henceforth be rigid on the bar 23, and will simply reciprocate therewith but will not rock relative thereto. The shaft 11, having been 85 again set into motion the regular shuttle movements will proceed as before through the action of cam 31, bar 23, lever 19, 22, etc. Thus it will be seen that when the regular shuttle movement ceases I impart a movement to the shuttles to draw off enough slack thread for the special purposes herein set forth. I prefer to operate this additional movement from the jacquard shaft as the latter continues to operate even when the 90 regular shuttle movement ceases, but I do not wish it to be understood that I am obliged to take such operating force direct from the jacquard shaft.

From the above it will be apparent that 100 the device is automatic and very simple, both in construction and operation.

I have described one form of my invention in detail for the purpose of fully teaching the application thereof, but with no intention of limiting the scope of my invention to the specific form herein shown.

Having described my invention what I claim is:

1. An embroidering machine of the movable tambour frame type, an operating shaft therefor, and shuttle mechanism, said shuttle mechanism including movable shuttles, means operated by said operating shaft for imparting the usual operations to the shuttles, jacquard operating means and means operated thereby for operating the shuttles to cause the drawing out of shuttle threads and adapted to be operated while the said embroidering machine operating shaft is not 115 effecting the operation of the shuttles.

2. An embroidering machine of the movable tambour frame type, including an operating shaft and shuttle mechanism, said shuttle mechanism comprising a throat plate 125 having needle apertures, movable shuttles having thread delivery apertures, means operated by the operating shaft for imparting the usual operations to the shuttles to move them back and forth on each 130

side of the throat plate needle apertures, jacquard operating means and means operated by the jacquard operating means for operating the shuttles to cause them to be so moved as to carry their thread apertures away from the thread apertures of the throat plate, only in one direction, and return, and adapted to operate said shuttles while the means for imparting the usual operations to the shuttles is not effecting the operation of the shuttles.

3. An embroidering machine of the movable tambour frame type, including an operating shaft therefor, and shuttle mechanism, said shuttle mechanism including movable shuttles, means operated by said operating shaft for imparting the usual operations to the shuttles, jacquard operating means and means operated thereby for causing an additional movement of the shuttles for drawing out additional shuttle threads and adapted to operate the shuttles while the said embroidering machine shaft is not effecting the operation of the shuttles.

25 4. An embroidering machine of the movable tambour frame type, including an operating shaft and shuttle mechanism, said shuttle mechanism comprising movable shuttles, means operated by the operating shaft for imparting the usual operations to the shuttles, jacquard operating means and means operated by the jacquard operating means for operating the shuttles to cause the drawing out of shuttle thread and 30 adapted to be operated during the operation of the shuttles by the means for producing the usual shuttle movements.

5. An embroidering machine of the movable tambour frame type, including a shuttle mechanism comprising a throat plate, movable shuttles, means operated with the embroidering machine for imparting the usual operations to the shuttles, jacquard operating means and means operated by the jacquard operating means for operating the shuttles to cause the drawing out of additional thread between the shuttles and throat plate, and adapted to be operated during the operation of the shuttles by the means for producing the usual shuttle movements or while the latter is not effecting the operation of the shuttles.

6. An embroidering machine of the movable tambour frame type, including a shuttle mechanism comprising a throat plate, movable shuttles, means operated with the embroidering machine for imparting the usual operations to the shuttles, jacquard operating means and means operated by the jacquard operating means for operating the shuttles to cause the drawing out of additional thread between the shuttles and throat plate, and means operated by the jacquard operating means for throwing said latter operating means into and out of operation,

said shuttle operating means being adapted to simultaneously effect the operation of the shuttles.

7. An embroidering machine, including shuttle mechanism embodying movable shuttles, a movable member for operating the shuttles, means operated with the embroidering machine for reciprocating said movable member to impart the usual operations to the shuttles, jacquard operating means, and means operated by the jacquard operating means for oscillating said movable member to impart movement to the shuttles simultaneously with the reciprocating of the movable member.

8. An embroidering machine of the character described, including shuttle mechanism embodying movable shuttles, a movable member for operating the shuttles, an operating shaft, means operated thereby for reciprocating said movable member to impart the usual operations to the shuttles, jacquard operating means, means operated by the jacquard operating means for oscillating the movable member to impart movements to the shuttles simultaneously with the movements imparted by the operating shaft, and means operated by the jacquard operating means for throwing said last mentioned shuttle operating means into and out of operation.

9. An embroidering machine of the character described, including shuttle mechanism having movable shuttles, a reciprocating member operated with the embroidering machine and arranged to operate the shuttles, a rocking member fulcrumed to the reciprocating member, jacquard operating means and means operated by the jacquard operating means for oscillating said reciprocating member through said rocking member, to operate the shuttles.

10. An embroidering machine of the class described, including a shuttle mechanism comprising movable shuttles, a reciprocating member operated with the embroidering machine for operating the shuttles to cause the usual shuttle operations, jacquard operating means, a rocking member operated by the jacquard operating means, fulcrumed to the reciprocating member, means operated by the jacquard operating means for locking and unlocking said rocking member, and means operated by the jacquard operating means for operating said rocking member to operate the shuttles.

11. In an embroidering machine of the character described, shuttle mechanism including movable shuttles, an operating shaft, a reciprocating element operated from said shaft and adapted to operate the shuttles for the stitching operations, a rocking member fulcrumed to the reciprocating element, power means operating while said shaft is inoperative, means operated by the said

power means for oscillating the reciprocating element, and means for unlocking said rocking element and throwing said means for oscillating said reciprocating element into operation.

12. In an embroidering machine of the character described, shuttle mechanism embodying movable shuttles, a shuttle drive and a lever for operating the same, an operating shaft, a movable element fulcrumed on said shaft, means operated by said shaft for reciprocating said movable element, a rocking member fulcrumed to said movable

element and arranged to operate said lever, locking means for the said rocking member, a jacquard shaft having a cam, means operated thereby for rocking said movable element and means for simultaneously throwing said latter means into operation and unlocking said rocking member.

Signed at the city, county and State of New York, this 15th day of December, 1911.

JOSEPH A. GROEBLI.
